UNITED STATES PATENT OFFICE.

MORRIS PARKER HENVIS, OF NORFOLK, VIRGINIA, ASSIGNOR OF ONE-HALF TO CHARLES E. PARKER.

WINDOW MECHANISM.

No. 839,759.

Specification of Letters Patent.

Patented Dec. 25, 1906.

Application filed November 9, 1905. Serial No. 286,606.

To all whom it may concern:

Be it known that I, MORRIS PARKER HENVIS, a citizen of the United States, residing at Norfolk, in the county of Norfolk and State 5 of Virginia, have invented certain new and useful Improvements in Window Mechanisms, of which the following is a specification.

My invention relates to window mechanisms for cars, steamboats, and the like.

10 The object of the invention is to provide means for raising and lowering the windows. Further objects and advantages will be more fully understood by having recourse to the accompanying drawings, forming a part 15 of this specification, in which—

Figure 1 is a cross-sectional view taken on the line 1 in Fig. 2. Fig. 2 is a front or inside view, one side being removed to show the mechanism. Fig. 3 is a plan of the U-shaped spring-ended rod. Fig. 4 is a side view of the same and is an enlargement of that shown in Fig. 1. Fig. 5 is a side view of a modified form of spring-ended rod. Fig. 6 is a part front view of the window and its frame, 20 showing the springs inserted in the side of the frame when the windows are provided with transoms. Fig. 7 is a plan of the counterbalance-weight. Fig. 8 is a perspective view of the elevator bar or carrier. Fig. 9 is a side 25 view of one end of the counterbalance-weight, showing a part sectional elevation setting out the mode of fastening the suspending-ropes thereto.

In the drawings like reference-numerals 30 indicate similar parts in all the views.

1 and 2 are the side and bottom boards of the housing, respectively.

3 is the window-sill, having a sloping outer portion, as shown.

40 4 is the window-frame, and 4^a is the top portion thereof, upon which the roof rests in the ordinary manner.

5 is the window-sash provided with glass and may be with or without transoms.

45 6 is a bar or bead placed on the outside of the sash at an angle, as shown in Fig. 1, and is for the purpose of forming a stop against which the sash bears when closed. 7 is a similar bead or bar on the inside of the sash and is 50 for preventing the sash from being pulled too far inwardly when the window is to be opened.

8, Fig. 1, is a slot or elongated opening slightly longer than the width of the sash 5

and of such size as to permit the sash to be lowered in it, as shown by the dotted lines in 55 Figs. 1 and 2.

9 is an elevator bar or carrier normally in the position as indicated in Figs. 1 and 2, but when the sash is pulled inward the lower part of the sash 5 rests upon the bar and when the window is lowered it pushes the bar downward and subsequently causes the window to ascend automatically by a weight when a certain spring is released, as will be herein-after described. The bar or carrier is guided 60 in a vertical position by means of the vertical bars or beading 10, secured at some convenient point below the window-sill 3.

11 is a counterbalance-weight and is adapted to balance the weight of the bar 9 and the 70 window when it is to be raised and lowered; but when the window is closed, as shown in Figs. 1 and 2, the weight keeps the bar 9 close up into the slot 8, Fig. 1, and flush with the upper surface of the sill 3. 75

12 is a rope or cord connected to the weight 11 and the bar 9 and passes over the pulleys 13, supported on their axles 13^a and placed in the pocket or recess 13^b, Fig. 1.

14 is the fastening-point for the ropes 12 80 on the bar 9 and is placed beneath the same, as shown, the point being below the center of the pulleys 13, so that the bar may come closely up and be held to the sill 3.

While the rope 12 is shown secured to the 85 weight 11 by ring-bolts or screw-eyes 15, I prefer to bore a hole through the weight near each of its ends and cause the rope to pass through them, then tying a knot 16, Fig. 9, to prevent the rope from slipping through 90 the holes, as shown.

The weight 11 is provided with holes through which pass the rods 17, secured to the floor-timbers and at some convenient place under the sill 3, and are for the purpose 95 of guiding the weight and preventing it from vibrating when the device is used in cars and on steamboats.

I show two rods in the drawings; but if the window is small one may be sufficient, or the 100 rods may be replaced by the bar or bead 18, Fig. 1, if desired, thus dispensing with the apertures 19, Fig. 7, in the weight, also the rods 17.

The weight 11 rests upon the blocks or bars 105 20 when the window is closed and also abuts

upon the block 21 when the weight rises and the window is open.

The elevator bar or carrier 9 is provided with shoulders 22, Fig. 8, so as it may not rise above the upper surface of the sill 3, as shown in Fig. 1.

23 is a spring frame or bar bent to form a U-shaped figure and bears upon two sides of the sash when it is being raised or lowered 10 and upon its bottom portion when raised, the bottom part 23^a of the bar or frame being extended from the sash 5 for a handle or pull, as will be described hereinafter. The free ends of the bar or frame 23 terminate in 15 coiled springs 24 of two or more convolutions and ending in a short portion 25, which is adapted to fit in bushings 26 in the top of the window-frame 4^a, as shown in Figs. 1 and 2. The lower portion 23^a of the frame or rod 23 20 is inwardly bent into a curve 27 and still further extended from the sash 5, as at 28, Fig. 3, for the purpose of permitting the hand to be inserted to grasp the handle 29 for pulling the sash inward so it may rest upon the elevator bar or carrier 9 when it is desired to lower the window.

30, Fig. 5, is a modified form of spring and may be used where it is not practical to apply the coiled springs shown at 24.

30 The lower portion of the sash 5 is provided with two or more hooks 31, by which it may be pulled from its position (shown in Fig. 1) by means of the lower portion of the bar or frame 23 preparatory to opening the window.

35 32 represents stop-pins placed on the window-frame or upon the bead or stop 7, their function being to prevent the frame 23 from being pulled out too far, as the hooks 31 leave the part 23^a when the sash starts to descend, and when the handle 29 is released the force of the springs 24 cause the U-shaped frame 23 to press against the sash 5 in striking alinement with the hooks 31 when the sash is again raised.

45 The sill 3 is provided with suitable grooves to allow the hooks 31 to pass through the same, though I do not show them, such being a matter of construction and adaptation.

33 is a pocket in the side members of the 50 window-frame 4 for the springs 24 and is a modification to be used when the windows of a railway-car or steamboat are provided with transoms or where the upper portion of the window-frames are inaccessible.

55 The operation of the described mechanism is as follows: When the window is closed, the lower part of the U-shaped rod-frame 23 is pulled toward the inside of the car, saloon, or room by means of the handle 29, which places 60 the lower edge of the sash on top of the bar or carrier 9. Then a downward pressure of the sash carries it squarely down between the car-facing and lifts the weight 11. During this action the lower portion 23^a of the U-shaped frame bears against the side members of the

sash 5, which holds the window down by friction and acts so as to prevent rattling of the sash. To raise the window, the handle 29 is pulled slightly inward, causing the sash to rise fast or slowly by the weight 11 and may be 70 made to close entirely or partly open, as may be desired. When the window is to be completely closed and after it has risen as far as it will go, by releasing the handle 29 on the frame 23 the force of the springs 24 pushes the 75 sash outward in the position shown in Fig. 1 and may be subsequently opened without effort, which is not usual with other windows in use by reason of imperfect joints, inadequate handholds or pulls, and other defects. 80

Having described my invention, what I claim, and desire to secure by Letters Patent, is—

1. In an apparatus of the class described comprising a window-frame, facing-boards 85 or housing, a sill having an elongated opening, a sash adapted to pass in said opening and between the facing-boards or housing, a carrier or elevator bar adapted to close said opening in the sill when in a raised position, 90 guides for the carrier, a weight adapted to approximately balance the combined weight of the sash and the carrier, pulleys disposed in a pocket under said sill and above the carrier when in an elevated position, ropes or 95 cords passing over said pulleys and connected to said weight and the carrier, a stop-block for said weight when raised, guide-bars passing through the weight, a U-shaped bent rod secured to the window-frame having 100 springs at its free ends adapted to bear upon the sash, means for placing the sash upon said carrier or elevator bar by said spring-ended rod, means for automatically raising the sash when said rod is released from the 105 sash, and spring means for removing the sash from said carrier or elevator bar to the sill at an angle when the carrier-bar is raised. 110

2. In an apparatus of the class described comprising a window-frame, a sash, stop-bars disposed at an angle on the outside and inside of the sash, a window-sill, an elongated opening therein, a U-shaped bent rod secured to said window-frame at its top or sides and provided with springs on its free ends, said 115 opening adapted to bear against the sash, hooks on the lower portion of the sash normally in striking alinement with said spring-ended rod, a carrier-bar adapted to be vertically movable, means for placing the said sash on the carrier by the said hooks when the spring-ended rod is pulled inwardly, pins on the window-frame for stopping the movement of said rod when said hooks are disengaged therefrom during the lowering of the 120 window, means for raising the window when said spring-ended rod is released from the sash, means controlled by said spring-ended rod for causing the sash to leave the carrier 125 and engage one of the stop-bars or beading, 130

and means for closing said elongated opening in the sill by the carrier when the window is closed.

3. In an apparatus of the class described comprising a window-frame, a sash supported therein, facing-boards or housing, a sill on said facing having an elongated opening therein, a carrier-bar adapted to raise and lower the sash, means for closing said opening in the sill by the carrier-bar when the sash is raised, a rod bent to form a U-shaped figure having springs upon its free ends and secured for action in the window-frame, means for exerting a pressure by the spring to hold the sash in a normally closed position, an extension for a handle on the lower por-

tion of the said spring-ended rod, hooks on the bottom of the sash for engaging said rod to open the window, stops on said window-frame for limiting the movement of the rod when disengaged from the hooks, means for raising said sash by releasing the spring-pressure, and means for removing the sash from the carrier-bar when the window is raised. ²⁵

In testimony whereof I have hereunto affixed my signature, in the presence of two witnesses, this 30th day of October, 1905.

MORRIS PARKER HENVIS.
